UNITED STATES PATENT OFFICE.

DAVID HINDAHL, OF CHICAGO, ILLINOIS, ASSIGNOR TO HARRY S. HART, OF CHICAGO, ILLINOIS.

MAXIMUM-CAPACITY CAR.

Application filed March 1, 1924. Serial No. 696,114.

To all whom it may concern:

Be it known that I, DAVID HINDAHL, a citizen of the United States, residing at Chicago, in the county of Cook and State 5 of Illinois, have invented certain new and useful Improvements in Maximum-Capacity Cars, of which the following is a specification.

The present invention relates to maximum 10 capacity cars.

More particularly, the present invention relates to the construction of railway dump cars. Cars of this sort are commonly designed to deposit lading selectively outside 15 of the tracks or between the tracks between the trucks, which trucks are located adjacent to the two ends of the cars. If the lading to be deposited is relatively heavy such, for example, as rock ballast, the carrying capacity for such lading is limited not by the bulk thereof, but by the weight. Ballast cars in common use limit the amount 20 of rock ballast or other heavy ballast to that which may be carried by said car at 25 regions from which dumping may be conveniently accomplished between the trucks. Inasmuch as the distance between the trucks is limited by certain specifications, a problem 30 which has presented itself to designers of cars of this sort has been to so design the parts that a maximum of ballast up to the limit of weight may be carried without sacrificing the advantages of convenient dumping and without sacrificing 35 adaptability for the car for carrying lighter lading. Certain types of ballast cars which have been designed are quite inefficient when it is desired to carry other lading, such as coal, which is lighter in weight, 40 inasmuch as said cars do not economically utilize the space over the trucks.

An object of the present invention is to provide a construction which will permit the carrying of a maximum of heavy lading 45 up to the limit of weight, which car will also be efficient for carrying lading of lighter weight.

A further object is to provide an improved car for carrying a maximum of heavy lad-

ing, such as rock ballast, which should be 50 deposited selectively between the rails or outside of the rails and for carrying lading such as coal, which need not be dumped between the rails.

A further object is to provide an improved 55 car for efficiently carrying relatively heavy lading, which car will be economical of space for carrying lighter lading.

A further object is to provide an improved 60 car providing maximum carrying capacity for both heavy ballast and for light ballast.

Further objects will appear as the description proceeds.

Referring to the drawings—

Figure 1 is a view in longitudinal section 65 of one end of a railway dump car;

Figure 2 is a plan view, parts being shown in section, the sectional view being taken along the plane indicated by the arrows 2—2 of Figure 3;

Figure 3 is a transverse vertical sectional view taken along the plane indicated by the arrows 3—3 of Figure 1; and

Figure 4 is a sectional view taken along the plane indicated by the arrows 4—4 of 75 Figure 2.

The numeral 1 indicates a dump car having the side walls 2, 2, and end walls, one of which is indicated by the numeral 3. Trucks, one of which is located adjacent 80 to each end of the car 1 are illustrated diagrammatically by the wheels thereof which are indicated by the reference numerals 4, 4. According to the illustrated embodiment of the present invention, the car is provided 85 with dumping mechanism located between the trucks, said dumping mechanism comprising doors 5, 5, (one of which is illustrated in Figure 1), which doors 5, 5, are mounted for swinging movement about axes 90

disposed longitudinally of the car. Referring to Figure 1, a shaft 6 is provided carrying chains 7, 7 for operating the doors 5, 5. The dumping mechanism may be arranged for selective dumping either between 95 the trucks or outside thereof. The details of construction of the dumping mechanism between the trucks need not be described

herein inasmuch as such details are well known to those skilled in the art and inasmuch as said details do not constitute the present invention.

6 Each end of the car is provided with a sloping floor 8, which floors slope toward the adjacent ends of the doors 5, 5; that is to say, said floors 8, 8 are so sloped that lading located above said floors will tend 10 to move toward the doors 5, 5 when said doors are opened. Said floors should be disposed at such an angle relative to a horizontal plane that such lading as rock ballast will flow therefrom, that is to say, the angle 15 should be such that the force of gravity acting upon rock ballast located above said floors will be sufficient to overcome the resistance to flow due to contact between said floors 8, 8, and the ballast resting thereon. For this purpose it has been found by experiment that the angularity of the floors 8, 8, relative to a horizontal plane may be approximately 45 degrees with the car standing upon a horizontal track when said 20 car is designed for the carrying of rock ballast.

At each end of the car above the trucks 30 is a floor indicated by the numeral 9. The details of the construction of the floor 9 do not form a part of the present invention, but said floors should be so designed as to permit the discharge of lading therefrom to the sides of the car outside the rails. Any preferred design of floor may be used, many 35 of such designs being known to those skilled in the art. According to the illustrated embodiment of the present invention, the floors 9 may comprise sloping portions for directing lading laterally of the car, said sloping portions having their apex along the line marked by the angle 10. Swinging side doors 11, 11 may be provided, controlled in any preferred way, for permitting lading to flow from said floors 9 to the sides of the 40 car.

45 Cooperating with each sloping floor 8 is the reversely sloping floor 12, which floors 12, 12 are provided to support lighter lading at the ends of the car when said car is used for carrying lighter lading. Each sloping floor 8 extends to a line disposed transversely of the car, which line lies near the top of the car above the corresponding truck, indicated by the wheels 4, 4. In the 50 illustrated embodiment of the present invention, the top of each floor 8 lies in a vertical plane located substantially midway between the wheels 4, 4, of its adjacent truck. Each of said floors 8 is supported by a transversely extending bar 13, which bar may be supported by angles 14, one of which is illustrated in Figure 1. Angles 15 may also be provided for joining each of the floors 8 to the sides of the car.

60 It will be noted from the drawings that

the present invention has been illustrated in a car having wood as a considerable part of its construction. It will be understood, of course, that the invention is not limited to wooden cars or cars of any particular material, but in the event that it is preferred to use wood in the construction of the car, the present invention contemplates certain novel features for securing and supporting the wooden structure.

75 Referring to Figures 3 and 4, it will be noted that the center sill 16 has mounted on the two sides thereof the bolsters 17, 17. The cross-sectional configuration of each bolster 17 is illustrated in Figure 1. It will be noted that each bolster 17 comprises a sheet steel member 18 which has secured thereto at its lower extremities the angles 19, 19, and at its upper extremity the angle 20. Located adjacent to the angle 20, but disposed upon the opposite side of the member 17 is the Z-bar 21 which provides an abutment for receiving the lower portion of the floor 12. An angle 22 is secured on the upper side of the center sill 16, which angle 90 provides an abutment aligned with the abutments provided by the Z-bars 21, 21, so that a continuous abutment is provided transversely of the car for the corresponding 95 floor 12.

100 In operation, when it is desired to use the car for carrying rock ballast or other heavy lading, said heavy lading will be deposited in the car centrally thereof, being carried by the bottom portion between the trucks and by the sloping floors 8, 8, said heavy lading assuming an angle of repose which may be indicated by the line 23. When the car is to be used for the purpose of carrying lading which need not be dumped between the tracks, the entire car between the end walls thereof may be filled with such lading, only a small portion of the car between the sloping floors 8 and 12 at each 105 end of the car being unused at this time. 110 That portion of the lading above referred to which is located on and between the sloping floors 8, 8, will be directed through the doors 5, 5. That part of such lading which is located between the floors 8, 8, and the ends of the car will be directed through the swinging doors 11, 11. The car illustrated and described will shed all of the lading 115 whereby a maximum of convenience in handling is obtained.

120 Though a preferred embodiment of the present invention has been described in detail, it will be clear that many modifications may be made without departing from the spirit of the invention. It is intended to cover all such modifications that fall within the scope of the invention as defined by the appended claims.

I claim:

1. A dump car for efficiently carrying 125

either relatively heavy or relatively light lading comprising a car body having trucks adjacent to the ends thereof, dump means between said trucks, a sloping floor at each end of said car for directing lading to said dump means, a floor at each end of said car over the corresponding truck, sloping walls for directing lading to said last mentioned floors, each of said walls being disposed at an angle to its corresponding first mentioned floor and abutting against said first mentioned floor at a line intermediate of the height thereof.

2. A dump car for efficiently carrying either relatively heavy or relatively light lading comprising a car body having trucks adjacent to the ends thereof, dump means between said trucks, a sloping floor at each end of said car for directing lading to said dump means, a floor located between each of said first mentioned sloping floors and the adjacent end of said car, walls for directing lading to said last mentioned floors, said walls being angularly disposed to have abutting relation with said first mentioned floors, said first mentioned floors being extended to a region materially beyond said walls.

3. A dump car for efficiently carrying either relatively heavy or relatively light lading, comprising a car body having trucks adjacent to the ends thereof, dump means between said trucks, a sloping floor at each end of said car for directing lading to said dump means, means providing a receptacle at each end of said car beyond said sloping floors, said floors extending to lines disposed transversely of said car at regions near the top thereof, each of said receptacles providing means including a wall abutting against the underside of its corresponding floor along a line extending transversely of the car at a materially lower level than the top of said floor.

4. A dump car for efficiently carrying and dumping relatively heavy lading and lighter lading, comprising a body portion, trucks at the ends of said body portion for supporting same, dumping mechanism between said trucks, dumping mechanism over said trucks, and sloping floors and walls, arranged in pairs, extending transversely of the car body, walls and floors of each pair being adjacent to each other and reversely sloped to form an apex, said floors being disposed to direct lading to a region between said trucks, said floors extending to a region adjacent to the top of said car, said walls being disposed to direct lading to regions adjacent to said trucks and having abutting relation with said floors at regions materially lower than the upper extremities of said other floors.

5. A dump car comprising in combination, a car body, trucks for supporting same, slop-

ing floors for directing lading to a region between said trucks, each of said sloping floors lying above an adjacent truck between said trucks, and sloping walls for directing lading to regions adjacent to said trucks, 70 said sloping walls having abutting relation with the under-sides of said first floors at regions intermediate of the height of said floors.

6. In a dump car, in combination, a sloping floor for directing lading centrally of said car, a sloping wall having abutting relation with said sloping floor, a center sill, bolsters abutting said center sill, and angular means supported by said center sill and 80 said bolsters for forming abutments for said second mentioned sloping wall.

7. In a dump car, in combination, a sloping floor for directing lading centrally of said car and a sloping wall having abutting 85 relation with the under-side of said floor for directing lading toward an end of said car, said sloping floor being extended to a region materially above said sloping wall.

8. A dump car for efficiently carrying 90 either relatively heavy or relatively light lading, comprising a car body having a truck adjacent to an end thereof, dump means centrally of said car, a sloping floor located over said truck for directing lading 95 to said dump means, a sloping wall for directing lading to a region adjacent to said truck, said wall being disposed at an angle to said floor and abutting against said floor on the under-side of said floor at a line intermediate of the height thereof.

9. A dump car for efficiently carrying either relatively heavy or relatively light lading, comprising a car body having a truck adjacent to the end thereof, dump means located centrally of said car, a sloping floor over said truck for directing lading to said dump means, a sloping wall for directing lading to a region adjacent to said truck, said wall being angularly disposed 105 relative to and having abutting relation with said floor, said floor being extended to a region materially above said wall.

10. A dump car for efficiently carrying either relatively heavy or relatively light lading, comprising a car body having a truck adjacent to an end thereof, dump means disposed centrally of said car, a sloping floor above said truck for directing lading to said dump means, means providing a receptacle at said end of said car beyond said sloping floor, said receptacle providing means including a wall abutting against the underside of said floor at a line extending transversely of said car at a materially 110 lower level than the top of said floor.

11. A dump car for efficiently carrying and dumping relatively heavy lading and lighter lading comprising a body portion, a truck at an end of said body portion for 120

supporting same, dumping mechanism disposed centrally of said car, a sloping floor and a sloping wall reversely disposed relatively to one another to form an apex, said floor being disposed to direct lading to a region centrally of said car, said floor extending to a region adjacent to the top of

said car, said wall having abutting relation with said floor at a region materially lower than the upper extremity of said floor. 10

Signed at Chicago, Illinois, this 26th day

of February, 1924.

DAVID HINDAHL.
